GRID-TRIMMING APPARATUS

Max O. Kuhn, Cuyahoga Falls, Ohio, assignor, by
mesne assignments, to The Firestone Tire &
Rubber Company, Akron, Ohio, a corporation
of Ohio

Application January 8, 1938, Serial No. 184,054

8 Claims. (Cl. 164—20)

This invention relates to grid-trimming apparatus, and more especially it relates to apparatus for removing surplus metal from the margins of grids such as are employed in storage batteries.

Apparatus heretofore employed for the purpose mentioned has been of the punch type wherein a downwardly moving punch severed the grid from a casting, and then elevated the scrap material, by reason of the frictional engagement of the latter with punch, above the plane of the died-out grid to permit the removal of the grid, the scrap subsequently being stripped from the punch and removed from the machine. The apparatus is satisfactory so long as the scrap is of sufficient size or width to remain in one piece. It is desirable, however, that the scrap or surplus metal on the grid-castings be as small as possible to avoid re-heating of the same, since one of the elements of the casting alloy is somewhat volatile. When the grid-castings are so constructed the trimming apparatus described operates but imperfectly due to fracture and crumbling of the scrap metal.

The chief objects of this invention are to avoid waste of material such as occurs when the grid-castings include excessive material requiring to be trimmed therefrom; and to provide improved grid-trimming apparatus. More specifically, the invention aims to provide grid-trimming apparatus wherein the trimmed grid and the scrap material are separated and removed without requiring the lifting of the scrap or trimmings from its support. Other objects will be manifest as the specification proceeds.

35 Of the accompanying drawings:

Figure 1 is a front elevation of apparatus embodying the invention, in its preferred form, in operative or trimming position, and the work therein;

40 Figure 2 is a front elevation, on a larger scale, of the trimming instrumentalities, in inoperative position;

Figure 3 is a view similar to Figure 2 showing the parts in the initial phase of operation;

45 Figure 4 is a plan view of a portion of the trimming instrumentalities, on a larger scale, as viewed from the line 4—4 of Figure 2;

Figure 5 is a section on the line 5—5 of Figure 4;

50 Figure 6 is a section, on a larger scale, on the line 6—6 of Figure 1, showing the position of the trimming elements during a grid-trimming operation;

55 Figure 7 is a section similar to Figure 6 show-

ing the trimming elements at a subsequent stage of operation;

Figure 8 is a section similar to Figures 6 and 7 showing the trimming elements at the final stage of operation;

5 Figure 9 is a plan view of a grid casting before it is trimmed; and

Figure 10 is a plan view of the grid after it is trimmed.

Referring first to Figure 1 of the drawings, 10 there is shown a press which is generally of well-known construction. It comprises a frame 15 in which is mounted a vertically reciprocable press head 16. A crank shaft 17 mounted in the top of the press is employed to reciprocate 15 press head 16, said crank shaft carrying a gear 18 on one end thereof by means of which it is driven from a primary source of power (not shown), as is well known in the art. The press also includes a bed plate 19 that is positioned 20 below the press head 16, and carries a die that cooperates with a punch carried by the said press head for trimming surplus material from the grid castings, as subsequently will be explained.

Referring now to Figure 9, there is shown a 25 grid casting 21 in the untrimmed condition in which it is presented to the grid trimming apparatus. As shown, each grid casting 21 is provided near one end, at opposite sides thereof, with centering or guide holes 22, 22, and at the 30 other end with securing indentations 23, 23, the latter being provided for engagement with respective pins on a conveyor mechanism that carries the grid castings to the press, and carries the trim or scrap material away therefrom. Figure 35 10 shows the grid casting as it appears after the surplus material has been trimmed therefrom.

The grid castings 21 are carried to the trimming mechanism by means of an endless conveyor 25 to which is secured a succession of 40 upstanding pointed studs or prongs 26, 26. The latter are so spaced that the indentations 23 of the grid castings 21 will engage the adjacent sides of two spaced prongs. The prongs 26 are 45 positioned at one lateral margin of the conveyor 25 and serve to propel the grid castings along a platform (not shown) disposed beside the conveyor, and into position between a punch and die presently to be described. The conveyor 25 50 is mounted upon suitable pulleys of which two pulleys, 27 and 28, are shown in Figure 1. The conveyor 25 is advanced intermittently a determinate distance in timed relation to the reciprocation of the press head 16 so as to present suc- 55

cessive grid castings 21 to the action of the press, and to this end the pulley 27 is mounted upon a shaft 29 that also carries a four-tooth ratchet 30. The latter is engaged by a pawl 31 carried by an arm 32 that is pivotally mounted upon said shaft 29, the free end of arm 32 being connected by a link 33 to a lever arm 34 pivotally mounted at 35 on the frame of press 15. The lever arm 34 is connected by a link 36 to one end of a vertically reciprocable slide 37, one end of which carries a cam roller 38 and the other end of which carries a cam roller 39. Cam rollers 38, 39 are engaged by respective cams 40, 41 that are mounted upon a shaft 42 journaled in a support 43 on one side of the frame of press 15, said shaft 42 being driven by means of a bevel gear 44 that is mounted thereon and meshed with a bevel gear 45 carried by crank shaft 17 on the opposite end of the latter from gear 18. The arrangement is such that cam 40 moves slide 37 downwardly and cam 41 moves it upwardly, in alternation, to effect oscillation of the lever arm 34 and thereby to turn the shaft 29 and pulley 27 thereon angularly a determinate distance. A spring-tensioned automatically operated stop-pawl 46 may be provided for holding the shaft 29 in fixed position after it has been turned angularly by the pawl 31. Mounted upon the bottom of the press head 16 is an elongate punch holder 48 that extends laterally beyond the press head, at the end thereof from which the grid castings 21 approach the trimming station, and is provided thereat with a yieldingly mounted presser pad 49. The latter is connected to the punch holder 48 by means of stud bolts 50, 50, and spacer members 51, 51 of elastic material, such as rubber, are mounted upon the stud bolts 50 between the pad and the punch holder. The stud bolts extend freely through the punch holder, the arrangement being such that the pad may be forced toward the latter against the yielding pressure of the spacer members 51. The presser pad 49 cooperates with a fixedly mounted plate 52 positioned atop of the bed plate 19 for pressing and flattening successive grid castings 21 immediately prior to the moving of the latter to trimming position. Trimming of the grid castings 21 is effected by means of a punch and die of which the punch member 55 is secured to the punch holder 48 and the die member 56 is mounted upon the bed plate 19. The die member 56 is formed with a die opening 57, best shown in Figure 4, for cooperation with the punch 55, the latter having the same profile as said die opening 57. The punch holder 48 also carries a yieldingly mounted stripper plate 58 that is centrally apertured to enable the punch 55 to move therethrough. The stripper plate 58 is secured to the punch holder 48 by means of headed pins 59, 59 that extend slidably through suitable apertures in the punch holder, and respective compression springs 60 are mounted between the punch holder and stripper plate for urging the latter normally downwardly toward the cutting end of the punch, which downward movement is limited by the heads of pins 59. In the inoperative, elevated position of the punch holder and punch, the stripper plate is disposed somewhat below the cutting end of the punch, as shown in Figure 2 and Figure 8. The arrangement is such that the stripper plate engages the grid castings before the punch, at the beginning of a grid-trimming operation, and is not lifted from the trimmed surplus material, after the trimming operation, until the punch has been withdrawn therefrom.

At each side of the punch 55 is a stud 61 that projects below the cutting end of the punch and is accommodated in a suitable aperture through the stripper plate 58. The function of the studs 61 is to enter the respective apertures 22 in the grid castings 21 and accurately to position the latter for engagement with the punch, the die 56 being formed with bores 63, 63 (Figure 4) for receiving said studs during the punching or trimming operation.

As shown in Figures 5 to 8 inclusive, the die structure 56 is cut away on its under side, from the die opening 57 to the rear of the structure, and a filler block 65 is mounted in a part of the cut-away space and secured to the bed plate 19. The arrangement is such as to provide an internal slot 66 through the rear of the die block 56, and said slot is aligned with an internal slot 67 formed in the bed plate 19, said slot 67 constituting a continuation of slot 66 and extending to the rear marginal face of said bed plate. Positioned within the die opening 57 is a die pad 68, the latter being of substantially less thickness than the depth of the die opening, and being yieldingly mounted upon a plurality of compression springs 69, 69, Figures 4 and 5. The springs 69 normally urge the die pad 68 upwardly, and in inoperative position the top face of the die pad is flush with the top face of the die block, the upward movement of the die pad 30 being limited by a plurality of cap screws 70, 70 that are threaded into the bed plate 19 and have their heads disposed in sockets formed in respective bosses 71 that project downwardly from the under side of the die pad, the bed plate 19 being recessed at 72, 72, Figure 5, to receive said bosses in the depressed position of the die pad. Yieldingly mounted in suitable slots in the top face of the die pad 68 are metal strips 73, 73 that extend transversely of the pad from the front margin to the rear margin thereof. The strips 73 normally are disposed slightly above the top face of the die pad, but may be depressed under pressure, as when the punch 55 operates to trim a grid casting, the function of the strips being to break the adhesion between the grid casting and the die pad in case the casting should stick to the latter. One upper corner of each strip 73 is beveled, as shown in Figure 5, so as to enable the grid castings readily to slide thereover while being moved into trimming position beneath the punch. The stroke of the press head 16 is such that in the operation of trimming a die casting, the punch 55 will force the die pad 68 downwardly into the die opening almost to the bottom of the latter, and in this position the top face of the die pad is substantially in alignment with the bottom of slot 66, so that a trimmed grid casting may be moved rearwardly off the die pad and into said slot.

In order to move the trimmed grids off the die pad and into slot 66, it is necessary to retain the die pad in its depressed position, for a brief interval at least, after the punch 55 has been lifted. To this end the die pad is provided with two, downwardly projecting studs or posts 75, 75 that extend freely through respective bores in the bed plate 19. The lower end of each post 75 is joined, through the agency of an adjustable connection 76, with a slotted yoke 77 that is slidably mounted for reciprocatory movement in a bracket-like frame member 78 mounted upon the bottom face of the bed plate 19. Each yoke 77 carries a cam roller 79 that is engageable with a rotary cam 80, said cams being mounted 75

upon a driven shaft 81 that is journaled in the frame member 78. Exterioly of said frame member the shaft 81 extends laterally toward that side of the press that carries the driving gear 18, and is there journaled in a bearing bracket 82 and provided with a sprocket 83. A sprocket chain 84 connects sprocket 83 with a sprocket 85 on a countershaft 86, and a second sprocket 87 on the latter is connected by sprocket 10 chain 88 with a sprocket 89 mounted upon the crank shaft 17, beside gear 18 thereon.

The arrangement is such that the crank shaft 17 rotates the two cams 80 in determinate time relation to the up and down movement of the press head 16 and punch 55. The cams 80 are identical in shape and are arranged in the same angular position with relation to shaft 81. The chain 84 is driven in the direction indicated by the arrows in Figures 6 and 7 so that the cams 20 80 are driven in counter-clockwise direction as viewed in the said Figures 6 and 7. The cams 80 are out of engagement with the cam rollers 79 throughout most of their rotative movement, with the result that the springs 69 support the die pad 68 in elevated position, as shown in Figure 8, which is the normal inoperative position of the pad. During a grid trimming operation, the punch 55 descends upon the grid casting 21 upon the die structure, thus shearing the surplus material about the margins of the grid, and forcing the die pad 68 with the trimmed grid thereon downwardly to the position shown in Figure 6. Immediately the die pad reaches this position the cams 80 engage the cam rollers 79, so that 30 as the punch 55 rises the die pad is retained in depressed position, against the pressure of springs 69, by said cams, as shown in Figure 7. It is during this interval that the strips 13, which have been depressed by the pressure of the punch 55 thereon, resume their normal positions above the top face of the die pad and thus break any adhesion that may be present between the die pad and the trimmed grid thereon. While the die pad is still depressed, the grid thereon is 40 removed in a manner presently to be described, the grid moving rearwardly and edgewise through the slots 66, 67 to the rear of the apparatus. Thereafter the cams 80 move out of engagement with the cam rollers 79 and the springs 50 69 elevate the die pad to the inoperative position shown in Figure 6.

The removal of trimmed grids from the die pad 68 is facilitated by having the press 15 disposed at an angle such that the die pad and slots 66, 67 slope downwardly toward the rear of the press, as shown in Figures 6 to 8, so that the grids readily slide by gravity through said slots after being given an initial impetus. For imparting the initial impetus to the trimmed grids 21, a blast of 60 air is utilized, and to this end the die block 56 is formed interiorly with a passage 91 extending from the rear of the pad alongside one end of the die opening 57 and across the front of the latter, there being a series of ports or delivery orifices 65 92, 92 extending from said passage to the die opening, said ports being disposed just above the top of the die pad 68 when the latter is in the depressed position shown in Figures 6 and 7. The inlet to the passage 92, at the rear of the die block, connects with a pipe 93 extending to a 70 source of pressure fluid (not shown), a portion of said pipe being mounted upon the front of the press, as shown in Figure 1, and there provided with a valve 94 having an operating lever that 75 projects into the path of a dog 95 carried by the

press head 16, the construction and arrangement being such that the dog 95 operates the valve-lever to open the valve only during the initial phase of the rising movement of the press head. 5 At this time the die pad and punch are substantially in the positions shown in Figure 7, which figure shows a grid 21, in broken lines, moving off the die pad and into slot 66.

At the rear of the press there is provided means for receiving the grid plates 21 as they emerge 10 from the slot 67, said means comprising a pair of parallel downwardly inclined rails, such as the rail 97, Figure 7, which rails are arranged to engage the respective ears at opposite ends of the grids and thereby pendulously to support them. 15 Mounted between the rails 97, and extending rearwardly from the delivery orifice of the slot 67, is a downwardly sloping plate 98 adapted frictionally to engage the trailing margin of the grids 20 21, as the latter slide down the inclined rails 97, and gradually to guide the grids to vertical position.

When the die pad 68 is depressed by the punch 55 during the trimming of a grid 21, the lower 25 face of the die is spaced slightly above the bottom of the die opening. If, however, a trimmed grid adheres so tenaciously to the die pad as not to be removed therefrom by the means provided, the trimming of a second grid atop of the grid on the die pad will force the latter to the bottom 30 of the die opening. When this occurs it is desirable to stop the apparatus and remove the grid that is adhered to the die pad, the stopping of the apparatus being effected automatically by means of a spring pressed plunger 99. The head 35 or upper end of the latter extends into the die opening the proper distance to be engaged and depressed by the die pad only when the latter is forced below its normal depressed position. The plunger 99 extends through the bed plate 19 40 and bracket frame 78 and has its lower end positioned adjacent the end of an operating lever 100 of an electrical switch 101, the latter being operatively interposed in the electrical circuit that provides the power for operating the press. The 45 arrangement is such that when the plunger 99 is depressed it moves lever 100 to open switch 101 and thereby to cut off operating power to the press, to bring the latter to a standstill.

In the operation of the apparatus, the intermittently moving conveyor 25 brings the untrimmed grid castings to trimming position beneath the punch 55 while the press head 16 is in raised position. Upon descent of the press head, it is the stripper plate 58 that first engages the grid casting, and holds the marginal portions thereof firmly against the top face of the die block 56, the punch then passing through the stripper plate and into the die opening 57 to shear the surplus marginal portion from the grid. 55 The latter is forced downwardly into the die opening, against the spring-backed die pad 68, and as said die pad reaches its lowermost position, the cams 80 engage the cam rollers 79 so as to retain the die pads in depressed position upon subsequent rise of the punch 55. As the press head rises to withdraw the punch, dog 95 on the press head momentarily opens valve 94, with the result that a blast of air from the orifices 92 is directed against the adjacent margin of the trimmed grid 21, and the grid thereby projected through the slots 66, 67 to be received upon the rails 97 at the rear of the press. As the press head continues to rise, the die 55 is withdrawn from the die opening 57 and from the 75

scrap material that has been trimmed from the grid, said scrap material being firmly held by the stripper plate 58 until the punch is withdrawn. Subsequent to the withdrawal of the punch from the die, the cams 80 pass out of engagement with the cam rollers 79 and the springs 69 restore the die pad 68 to its elevated, inoperative position. This completes a cycle of operation which continuously and automatically is repeated. The movement of the conveyor 25 that brings untrimmed grid castings to the trimming position also removes the scrap trimmed from the grid by the previous trimming operation.

By removing the trimmed grids from the press at a different plane than that occupied by the scrap material, during the trimming operation, it is possible to dispose of the scrap material without lifting or flexing it, with the result that breakage is avoided even when the trimmed scrap is relatively thin and narrow. Thus the trim of the grid castings may be held to a relatively small proportion of the casting, with the result that losses due to re-heating are reduced.

Modification may be resorted to without departing from the spirit of the invention, or the scope thereof as defined by the appended claims.

What is claimed is:

1. In grid-trimming apparatus, the combination of a die having an opening therein defining the outline of the grid to be trimmed, a reciprocable punch operating through said opening, a die pad in alignment with said opening, yielding means normally urging said die pad out of said opening, and rotary power-driven means operating in determinate time relation to the movement of the punch and adapted mechanically to engage the pad structure for restraining movement of the pad in opposition to said yielding means.

2. In grid-trimming apparatus, the combination of a die having an opening therein defining the outline of the grid to be trimmed, a reciprocable punch operating through said opening, a die pad in alignment with said opening, supporting means for said die pad normally urging it out of said die opening, and enabling it to be displaced under pressure of the punch, and cam means for retaining the pad in displaced position for a determinate interval after pressure of the punch is removed therefrom, said means having adjustable connection with the pad structure.

3. In grid-trimming apparatus, the combination of a die having an opening therein defining the profile of the grid to be trimmed, a reciprocable punch operating through said opening, a die pad in alignment with said opening, supporting means for said die pad normally urging it out of said die opening and enabling it to be depressed under pressure of the punch, means for retaining the pad in depressed position for a determinate interval after pressure of the punch is

removed therefrom, and means for sliding a trimmed grid off the die pad while the latter is in depressed position.

4. In grid-trimming apparatus, the combination of a die having an opening therein defining the profile of a grid to be trimmed, and formed with a slot coextensive with one side of said opening and extending laterally therefrom through the die wall, a reciprocable punch operating through said opening, a die pad in alignment with said opening, yielding means normally urging said die pad out of said die opening and enabling said pad to be depressed by pressure of the punch thereon, means for retaining the die pad in depressed position as the punch rises therefrom, and means for moving a trimmed grid laterally off said die pad and through the die slot while the die pad is retained in depressed position.

5. In grid-trimming apparatus, the combination of a punch, a die, a yieldingly mounted die pad within the die opening against which the trimmed grid is pressed by the punch, and a plurality of parallel strips extending locally across the die pad and normally yieldingly urged to a position above the work-engaging surface thereof for breaking the adhesion thereto of a trimmed grid thereon.

6. A combination as defined in claim 5 in which the punch, die, and die pad are disposed in inclined position to enable trimmed grids to slide from the die pad, the yieldingly mounted strips on the latter being disposed parallel to the inclination of the pad.

7. In grid-trimming apparatus, the combination of a punch, a die, a yieldingly mounted die pad within the die opening against which the trimmed grid is pressed by the punch, and a plurality of strips extending across the die pad and yieldingly urged to a position above the work-engaging surface thereof for breaking the adhesion thereto of a trimmed grid thereon, each of said strips being beveled along one upper margin thereof to enable untrimmed grids readily to slide thereon in moving to trimming position beneath the punch.

8. In grid-trimming apparatus, the combination of a die having an opening therein defining the profile of the grid to be trimmed, a reciprocable punch operating through said die opening, a die pad in alignment with said opening, a yielding support for said pad normally urging it out of said opening and enabling it to be displaced by pressure of the punch thereon, and cam means operating in determinate timed relation to the reciprocation of the punch and engageable with the die pad structure, when the latter is displaced, to retain it in displaced position for a determinate interval after the pressure of the punch is removed therefrom.

MAX O. KUHN. 60
